CLAIM

The ornamental design for a display screen with animated graphical user interface, as shown and described.

DESCRIPTION

FIG. 1 is a front view of a first image in a sequence showing a first embodiment of a display screen with animated graphical user interface;

FIG. 2 is a front view of a second image thereof;

FIG. 3 is a front view of a third image thereof;

FIG. 4 is a front view of a fourth image thereof;

FIG. 5 is a perspective view of the design shown in FIG. 1 on a device;

FIG. 6 is a front view of a first image in a sequence showing a second embodiment of a display screen with animated graphical user interface;

FIG. 7 is a front view of a second image thereof;

FIG. 8 is a front view of a third image thereof;

FIG. 9 is a front view of a fourth image thereof; and,

FIG. 10 is a perspective view of the design shown in FIG. 6 on a device.

The ornamental design includes a graphical user interface. The unevenly spaced broken lines illustrate a device and the perimeters of a display screen and form no part of the claimed design. The other broken lines illustrate portions of the graphical user interface which form no part of the claimed design.

The appearance of the transitional image sequentially transitions between the images shown in FIGS. 1-4 for the first embodiment, and between the images shown in FIGS. 6-9

(Continued)

for the second embodiment. The process or period in which one image transitions to another image forms no part of the claimed design.
